United States Patent

Des. 237,431
Patented Nov. 4, 1975

237,431

DISPLAY STAND OR THE LIKE

Donald L. Dean, 9331 Pioneer Blvd., Apt. 103,
Santa Fe Springs, Calif. 90670

Filed Apr. 5, 1974, Ser. No. 458,337

Term of patent 14 years

Int. Cl. D20—02; XD6—04

U.S. Cl. D6—20

FIG. 2

FIG. 3

FIG. 1

FIG. 4

FIG. 6

FIG. 7

FIG. 5

FIG. 8

FIG. 1 is a perspective view of a display stand or the like of my new ornamental design;

FIG. 2 is a front elevational view thereof;

FIG. 3 is a rear elevational view thereof;

FIG. 4 is a side elevational view taken from the side opposite that shown in FIG. 1;

FIG. 5 is a perspective view of a modified form of my new ornamental design of a display stand or the like;

FIG. 6 is a front elevational view thereof;

FIG. 7 is a rear elevational view thereof; and

FIG. 8 is a side elevational view taken from the side opposite that shown in FIG. 5.

I claim:

The ornamental design for a display stand or the like, as shown and described.
